BUCKLE

John R. Bryant, Springfield, Tenn., assignor of
one-half to Hatton N. Batson, Bowling Green,
Ky.

Application March 20, 1934, Serial No. 716,518

2 Claims. (Cl. 24—163)

This invention relates to a buckle, the general object of the invention being to provide a simple form of buckle for adjusting the straps of overalls or the like.

5 This invention also consists in certain other features of construction and in the combination and arrangement of the several parts, to be hereinafter fully described, illustrated in the accompanying drawings and specifically pointed out 10 in the appended claims.

10 In describing the invention in detail, reference will be had to the accompanying drawings wherein like characters denote like or corresponding parts throughout the several views, and in 15 which:

Figure 1 is a fragmentary view of a portion of overalls, showing the invention in use.

Figure 2 is a section on line 2—2 of Figure 1.

Figure 3 is a view of the buckle.

20 Figure 4 is an edge view of the buckle.

Figure 5 is a section on line 5—5 of Figure 1, with the strap omitted.

Figure 6 is a view of the frame of the buckle.

Figure 7 is a view of the sliding member thereof.

25 Figure 8 is a view of the hook or clip, with a part of the button in section.

Figure 9 is an edge view of the hook or clip, showing the same connected with the button and also showing a part of the overalls.

30 In these drawings, the letter A indicates a part of the overalls and the letter B the straps thereof. A hook or clip 1 connects each strap to a button a of the overalls, each hook or clip having a substantially rectangular upper part 2 through which

35 a part of the strap passes, with the limbs 3 and 4 depending from this part 2, with the limb 3 of greater length than the limb 4 and the lower end of this limb 3 is bent upwardly to provide a U-shaped part 5 for fitting around the shank of the

40 button a and the extremity of the U-shaped part is bent to form an eye 6, as shown more particularly in Figure 9. The lower end of the limb 4 is bent inwardly at right angles and this part is bent into U-shape, as shown at 7, with its lower

45 limb or the limb which is connected with the part 4 passing through the eye 6 and this U-shaped part 7 extends across the lower part of the space formed by the limbs 3 and 4, as shown in Figure 8, so as to hold the shank of the button in the U-shaped part 5 of the limb 3. Each of the limbs 3 and 4 is slightly bent outwardly, as shown in Figure 8.

50 Thus it will be seen that by pushing the limb 4 outwardly, the U-shaped part 7 is moved to one side so that the shank of the button can be

5 passed into the U-shaped part 5 of the limb 3 and then by releasing the limb 4, the parts will return to the position shown in Figure 8 and thus the U-shaped part 7 will prevent the shank of the button from moving upwardly and thus eliminate danger of the hook or clip 3 releasing itself from the button.

Each buckle C for adjusting the length of each strap B is composed of a rectangular shaped frame 8 having its ends bent inwardly at their centers to form the U-shaped parts 9 and a wire 10 is bent into an elongated loop 10 which is closed, as shown more particularly in Figure 7, with one end of the wire bent beyond the looped part to form the hook 11. The loop 10 fits over the bight 15 of one of the U-shaped parts 9 and is slidably arranged thereon and the hook 11 is adapted to engage the bight of the other U-shaped part 9, as shown in Figures 4 and 5. By pressing upon the loop 10, the hook 11 can be forced out of engagement with the bight of the loop with which it engages and then the member 10 can be moved outwardly so as to facilitate the passage of the straps B through the frame, as shown in Figure 20 2. As will be seen from this figure, a part of the strap is passed through the frame and over the member 10 and then the strap is brought back and one end is passed into a part of the frame and over the member 10, with the extremity of this end located between the two parts of the 25 strap, as shown at 12 in Figure 2. It will, of course, be understood that the buckle can be slid on the strap to adjust the length of the same, but when the buckle is to be removed from the strap, it is simply necessary to press upon the 30 member 10 to free the hook 11 from the part 9 with which it engages and then by sliding the member 10 on the other part 9, the buckle can be easily removed from the strap.

It is thought from the foregoing description 40 that the advantages and novel features of the invention will be readily apparent.

It is to be understood that changes may be made in the construction and in the combination and arrangement of the several parts, provided 45 that such changes fall within the scope of the appended claims.

What is claimed is:

1. A buckle of the class described comprising a substantially rectangular shaped frame formed 50 of an endless piece of material and having the central portion of each end piece bent inwardly into U shape, a tongue having an elongated slot therein through which passes the bight of one U-shaped part of the frame for pivotally and 55

slidably connecting the tongue with said U-shaped part, said slot extending to a point adjacent one end of the tongue the other end of the tongue having a hook for engaging the bight of the other U-shaped part.

2. A buckle of the class described comprising a substantially rectangular shaped frame having the central portion of each end piece bent inwardly to provide a U-shaped part, an elongated member having one end portion bent in parallel

relation to another portion to provide an elongated loop through which passes the bight of one of the U-shaped parts, the extremity of said bent end portion being bent to contact the other portion to close the space formed by the loop and the extremity of said other portion being bent into hook shape to engage the bight portion of the other U-shaped part.

JOHN R. BRYANT.
